UNITED STATES PATENT OFFICE.

FRANK L. PLATT, GEORGE N. HEIN, AND ROBERT R. IMPEY, OF SAN FRANCISCO,
CALIFORNIA.

SYRINGE-APPLICATOR.

1,321,550.

Specification of Letters Patent. Patented Nov. 11, 1919.

Application filed May 6, 1919. Serial No. 295,071.

To all whom it may concern:

Be it known that we, FRANK L. PLATT, GEORGE N. HEIN, and ROBERT R. IMPEY, citizens of the United States, residing at the 5 city and county of San Francisco and State of California, have invented certain new and useful Improvements in Syringe-Applicators, of which the following is a specification.

- 10 In the dental profession it has become necessary, when administering a local anesthetic during the extraction of teeth or the treatment of the jaw bone in order to obtain the best results from the anesthetic, to insert 15 or force the hypodermic needle into the bone tissue. The forcing of the needle point into the bone tissue requires considerable pressure to be placed on the needle and this is easily accomplished when straight needles 20 are employed, but it is often necessary under certain conditions to employ a curved needle, and the forcing of the point thereof into the bone tissue is almost impossible owing to the curvature of the needle and 25 brittleness thereof. When pressure is placed on the syringe barrel to force the point of a curved needle into the bone tissue, the needle buckles in its curved portion and often breaks, and in general is very unsatisfactory.

The present invention relates to what may be termed an adapter for use in connection with syringes between the syringe end and the needle, which permits of the use of a 35 straight needle angularly disposed relative to the syringe body, which overcomes the requirement for a curved needle which in certain cases is required, thus enabling a straight needle to be employed in all cases. 40 A further object of the present invention is to provide a construction whereby, when it is desired to force the needle point into the bone tissue, when the needle is disposed angularly of the barrel, pressure may be 45 placed on the needle at a point in direct line with the same, whereby the side strain thrust on the needle is overcome by the employment of the present adapter with a straight needle secured to the end thereof 50 and angularly disposed relatively to the barrel end. A further object is to provide a means whereby the needle may be subjected to a light tapping to more readily facilitate the forcing of the point thereof 55 into the bone tissue without the liability of

breaking the needle, which is always the case when curved needles are employed.

With the above mentioned and other objects in view, the invention consists in the novel construction and combination of parts 60 hereinabove described illustrated in the accompanying drawings, and set forth in the claims hereto appended, it being understood that various changes in the form, proportion, size and minor details of construction 65 within the scope of the claims may be resorted to without departing from the spirit or sacrificing any of the advantages of the invention.

To more fully comprehend the invention, 70 reference is directed to the accompanying drawing, wherein the figure discloses a view in side elevation of the preferred embodiment of our invention applied to a syringe and disclosing the straight needle detach- 75 ably secured to the end of the applicator.

In the drawings, wherein like characters of reference designate corresponding parts, 1 indicates a conventional hypodermic syringe body of any suitable type, having 80 the usual plunger 2 and finger grips 3. Secured in any suitable manner, preferably by being detachably threaded to the discharge end of the syringe barrel 1' is the base 4 of the preferred form of our applicator 5, the 85 base being in line with the barrel 1 and having extended from the outer end thereof at any suitable angle or curvature an extension 6, to which is detachably secured the needle base 7 mounting any suitable form of hypo- 90 dermic needle 8 of the straight type. Extending rearwardly from the base 4 and disposed in alignment with the needle 8 is a suitable stud 9 to which is detachably secured preferably by a slidable connection a 95 finger or thumb rest 10 of any suitable construction and length, the same being placed in alignment with the needle and overlying the syringe barrel to enable the operator to press thereon when using the syringe to 100 insure direct longitudinal pressure on the needle 8, either when injecting the fluid into the tissue or when inserting the needle point into the tissue. It will be apparent by the employment of our applicator wherein the 105 discharge end is angularly disposed or offset relatively to the base or body which is in line with the syringe barrel, that we are enabled by the use of this applicator to employ straight needles on all work, thus dis- 110

pensing with the necessity of purchasing straight needles for certain work and the unsatisfactory curved needles for other work, it being practically impossible to insert the 5 point thereof into the bone tissue.

While we have illustrated the adapter as having portions disposed angularly to each other, it is to be understood that a curved applicator may be equally as well employed, 10 just so long as the straight needle is capable of use in connection therewith and when attached thereto will lie outwardly from and be angularly disposed relatively to the syringe barrel.

15 Having thus described our invention what we claim is:

1. In combination with a hypodermic syringe, a straight needle associated therewith, an adapter for connecting the syringe barrel and needle to dispose the needle at 20 an angle relatively to the barrel, and a pressure receiving member extending from said adapter substantially in alinement with said needle.
2. In combination with a hypodermic syringe, a straight needle associated therewith, an adapter for connecting the syringe 25

barrel and needle to dispose the needle outwardly from the syringe end and at an angle relatively to the syringe barrel, and 30 a pressure receiving member extending from said adapter substantially in alinement with said needle and disposed angularly to said barrel to overlie the same.

3. In combination with a hypodermic 35 syringe, a straight needle associated therewith, an adapter for connecting the syringe barrel and needle to dispose the needle outwardly from the syringe end and at an angle relatively to the syringe barrel, a stud 40 extending from said adapter substantially in alinement with said needle and disposed angularly to said barrel, and a pressure receiving member detachably secured to said stud to overlie said barrel. 45

In testimony whereof we have signed our names to this specification in the presence of two subscribing witnesses,

FRANK L. PLATT.
GEORGE N. HEIN.
ROBERT R. IMPEY.
